Walter F. Herold, Bridgeport, Conn., assignor to
 The Bassick Company, Bridgeport, Conn., a
 corporation of Connecticut

Application December 20, 1934, Serial No. 758,382

6 Claims. (Cl. 155—164)

The present invention relates to improvements in chairs with tilting backs and particularly chairs of the so-called posture type, in which the back is arranged to be adjusted to fit the back of the user of the chair, and in which a resilient support is provided for the back. In chairs of this type heretofore in use coil springs were used for the purpose of providing a yielding or resilient support for the chair back, the latter being pivotally supported for tilting movement. In these structures the relatively moving metal parts of the pivot joint of the back were in contact and under pressure of the springs so that during relative movement there was considerable surface friction, with the result that the tilting action was irregular, frequent adjustments were necessary, and the parts would creak and squeak. Also because of the great leverage necessary, due to the distance between the axis of tilt beneath the chair and the point of engagement of the user's back with the chair back, very large and strong springs were necessary. They furthermore required frequent lubrication, and due to the constant presence of lubricant would collect dirt and dust and were apt to soil the floor covering should the lubricant drip. For the most part these springs, co-operated with levers or cams, the springs and the levers or cams having a number of frictionally engaging bearing surfaces under the relatively great pressure of the springs, all of which surfaces constituted wear points which would squeak under the slightest movement, unless constantly lubricated.

An object of the present invention is to provide a chair in which the tilting action of the chair back takes place in a hinge joint of rubber, the rubber being in the form of a tubular member disposed under permanent pressure between two coaxially movable members disposed one within the other and to each of which the rubber is in effect bonded or permanently secured, and relative movement between these members being resiliently effected by the torsional strain set up in the compressed rubber. Because of the compactness of this structure and the potential pressures obtainable within relatively small dimensions the joint may be conveniently placed at any desired position relatively to the chair seat, and whereby the various adjustments to be made by the user may be most conveniently made by easily operated and accessible means. Another object is to provide joint means which will be noiseless in operation, will not deteriorate to any appreciable extent even after long and excessive use, and will require no lubrication.

With the above and other objects in view, embodiments of my invention are shown in the accompanying drawings and these embodiments will be hereinafter more fully described with reference thereto, and the invention will be finally pointed out in the claims.

In the drawings:

Fig. 1 is a side elevation of a complete chair embodying a tiltable chair back mechanism according to one embodiment of my invention. 10

Fig. 2 is a vertical longitudinal sectional view of the chair back tilting and adjusting mechanism, according to the embodiment of the invention illustrated in Fig. 1.

Fig. 3 is a plan view thereof, the chair seat being removed.

Fig. 4 is a vertical sectional view taken along the line 4—4 of Fig. 2, the chair seat being removed.

Fig. 5 is a side elevation of a chair back tilting mechanism, according to a modified embodiment of my invention. 20

Fig. 6 is a forward end elevation thereof, the chair seat being removed.

Fig. 7 is a vertical sectional view taken along line 7—7 of Fig. 5.

Fig. 8 is a side elevation of a chair back tilting mechanism, according to another modified form of my invention.

Fig. 9 is a perspective view of the chair back tilting mechanism shown in Figs. 1 to 4, one of the spider arms being shown partially broken away. 30

Fig. 10 is a perspective view of the chair back tilting mechanism shown in Figs. 5 to 7.

Fig. 11 is a side elevation, with parts broken away and partially in section, of a chair back tilting mechanism according to a further modified form of my invention. 35

Fig. 12 is a forward end elevation thereof, the back member being removed, and parts of the mechanism broken away.

Fig. 13 is a top plan view, parts being broken away.

Fig. 14 is a perspective view of the chair back tilting mechanism shown in Figs. 11 to 13, the chair back member being shown partially broken away. 45

Fig. 15 is a side elevation of a further modified form of the invention.

Fig. 16 is a plan view thereof.

Fig. 17 is a perspective view of the chair back tilting mechanism shown in Figs. 15 and 16, the chair back member being shown partially broken away. 50 55

Fig. 18 is a plan view of the bracket bearing member employed.

Fig. 19 is a plan view of the tilting frame member employed.

5 Fig. 20 is a plan view of the tension adjustment lever member employed.

Fig. 21 is a perspective view of the joint element employed.

10 Similar reference characters indicate corresponding parts throughout the several figures of the drawings.

15 Referring to the drawings, and more particularly to Figs. 1 to 4 and 9 thereof, the chair comprises a base 10 of any suitable form upon which there is swivelly mounted, as by means of the threaded vertical adjustment swivel post 11, a chair seat 12, a pair of seat supporting angle-iron spider arms 13-13 being secured in the usual manner to the under side of the seat, and to the 20 post 11.

25 The tilting joint mechanism, according to my invention, is secured between the spider arms 13-13 at a point near the rear edge of the seat, and comprises a bracket having a pair of side arms 14-14 connected by an integral bridge strut portion 15, and having formed on their ends cylindrical bearing portions 16-16 disposed in aligned and spaced relation to each other. The side arms are secured between the angle arms 30 13-13 by means of rivets 17. The joint element comprises an outer tubular member 18, an inner tubular member 19, and a cylindrical body of rubber 20 between the members 18 and 19 and being in effect bonded to their surfaces, so that upon relative rotary movement between the members 18 and 19 the rubber body is put under torsional strain. In practice the rubber body is bonded to the inner member 19, as by vulcanization, and is then forced into the outer member 18 under great 40 pressure, its diameter prior to insertion in the member 18 being considerably greater than the interior diameter of the member 18, so that the rubber is thus highly compressed and is in effect bonded to the inner surface of the member 18 by 45 the great surface friction set up between them under compression.

50 The ends of the rubber body project beyond the ends of the outer member 18, as at 21-21, and the ends of the inner member 19 project beyond the rubber body and are provided with diametrically extending semi-circular cross-section grooves 22-22 for locking this inner member to the tilting frame member, as will presently more fully appear.

55 The tilting back supporting frame member 23 is of general U-shape in plan and is provided in its forwardly projecting arms with apertures 24-24 in which are engaged the ends of a tie-bolt 25 extending through the inner member 19, one 60 end of this tie bolt being headed, as at 26, and the other end having a nut 27 screwed thereon. Upon the inner sides of the arms of the tilting frame member 23, in diametrically extending relation to the holes 24-24, there are provided semi-circular cross-section ribs 28-28 which engage the 65 grooves 22-22 and thereby rigidly lock the inner joint member 19 to the tilting frame rubber 23, the member 19 providing a supporting spacer or strut between the arms of the tilting frame member. 70

75 Upon the bearing portions 16-16 there are formed integral flanges 29-29 having stop surfaces 30-30 and 31-31, angularly disposed with relation to each other, and against which the transverse portion of the tilting frame member

engages in its limit positions, the surface 30 being manually engaged by said transverse portion, as shown in full lines in Fig. 2, and the surface 31 being engaged in the limited tilting position, as shown in dotted lines.

5 Within the space between the bearing portions 16-16, a tension adjustment lever 32 is disposed and projects beneath the bridge portion 15, its collar portion 33 being engaged about the intermediate portion of the outer joint member 18 10 and secured thereto by a set screw 34, the member 18 having a recess 35 therein in which the end of the set screw locking engages. An adjusting screw 36 having a hand wheel or nut 37 at its end is engaged in a threaded opening 38 in 15 the end of the lever 32 and bears at its upper end upon the under surface of the bridge portion 15. It will be obvious that by adjusting the screw 36 the outer joint member 18 is rotated with respect to the bracket 14 and the inner joint member 19, 20 and through the torsional strain imposed on the rubber 20 any desired initial tension may be set up in the latter, the greater the initial tension the greater force required to tilt the tilting frame member 23, which latter is connected with the 25 chair back, as will presently more fully appear.

25 The transverse portion of the tilting frame member projects below the side arms and is provided upon its rearward face with a vertically disposed groove 39 in which is engaged the vertically disposed rib 40 of a vertical adjustment plate member 41, this plate member being adjustably connected to the tilting frame member by means of a bolt 42 extending through the plate member and through a vertical slot 43 in the 35 tilting frame member, a tightening nut 44 being engaged upon this bolt and provided with a sliding cross-rod 45 for manually turning it. By loosening the nut 44 the plate member may be vertically adjusted to any desired position, which 40 adjustment raises or lowers the chair back relative to the chair seat.

45 The plate member 41 is provided near its upper end and adjacent its vertical edges with ears 46-46 in which are engaged the ends of a shaft 47, upon which are also engaged ears 48-48 of a chair back supporting frame member 49. In order to obtain angular adjustment of the chair back supporting frame member 49 with respect to the chair seat a coil spring 50 is disposed between the frame member 49 and an upwardly extending ear 51 provided upon the upper end of the plate member 41, the frame member 49 having a pocket 52 formed therein in which one 50 end of the spring is engaged and the ear 51 having a pocket 53 formed therein in which the other end of the spring is engaged. This spring is located above the shaft 47, and below this shaft there is provided in the frame member 49 an adjusting screw 54 having a hand wheel 55 at one 60 end, its other end bearing against the outer face of the plate member 41. It will be obvious that by adjusting the screw 54 the frame member 49 will be angularly adjusted relatively to the chair seat. 65

65 A pair of vertical chair back supports 56-56 are secured to the ends of the frame member 49, and upon the upper ends of these supports there is mounted the chair back element 57, this element being preferably tiltably mounted, as at 70 58, so that its angle may be adjusted relatively to the supports 56 by means of an adjustment screw 59.

75 The tilting mechanism, according to my invention, gives full floating resilient support to the 75

chair back by the interposing of the compressed tensioned rubber body 20 between the outer and inner joint members 18 and 19, and by the disposition of the rubber ends 21—21 an outer joint member away from the sides of the arms of the frame 23, so that the relatively movable parts are entirely insulated by the rubber against frictional contact. When the back is tilted the building up of tension in the rubber body, while permitting an easy tilting action, prevents sudden or hard tilting to the limit position, and provides a smoothly resilient but at the same time a substantial support for the user's back. By adjusting the tension in the rubber body by means of the adjustment screw 36 the tensional resistance may be regulated to exactly suit the needs of the user of the chair, and this feature, in combination with the vertical and angular adjustment, provides a posture chair which may be made to accommodate itself in the most efficient and desirable manner to the individual requirements of the user. As no lubrication is required the parts will remain indefinitely in perfect working order without attention, and because of the absence of lubricant dirt and dust will not readily collect as has been the case with other types of mechanisms employed in posture chairs. Inasmuch as this type of chair is used for the most part by women, the cleanliness of the structure, and the ease with which its adjustments may be made are highly desirable and advantageous features.

In Figs. 5 to 7 and 10 I have illustrated a modified form of the invention in which the joint element is provided in the rear of the seat 12, and comprises a vertically disposed bracket member 60 having a pair of horizontal forwardly extending arms 61—61 integrally formed thereon, and which are respectively secured to the angle iron spider-arms 13—13 by means of rivets 62. A vertically extending groove 63 is provided in the rearward face of the bracket member 60 and is engaged by a vertically extending rib 64 formed on a joint supporting frame member 65, a vertical slot 66 being formed in the bracket member 60, which is engaged by a bolt 67, set in the frame member 65 and having upon its threaded end a nut 68, adapted to be tightened against the bracket member 60 to secure the frame member 65 in its vertically adjusted position. Obviously by loosening the nut 68 the frame member 65 may be vertically adjusted.

The frame member 65 is provided at the respective ends of its upper portion with a pair of rearwardly and upwardly extending arms 69—69, having bearing openings 70—70 therein in which are mounted the ends of the joint member, as will now more fully appear. The joint member comprises an outer tubular member 71, an inner tubular member 72, and an intermediate cylindrical body of rubber 73 between them, this rubber body being highly compressed and confined between the members 71 and 72 and being in effect bonded to their surfaces, so that upon relative rotary movement between the members 71 and 72 the rubber body is put under torsional strain. In practice the rubber body 73 is bonded to the inner member 72 as by vulcanization and is then forced into the outer member 71 under great pressure, its diameter prior to insertion in the member 71 being considerably greater than the interior diameter of the member 71, so that the rubber body is thus highly compressed and is in effect bonded to the inner surface of the member 71 by the greater surface friction set up between them under compression. The ends of the rubber project beyond

the ends of the outer member 71, as at 74—74, and the ends of the inner member 72 project beyond the rubber body and are provided with diametrically extending semi-circular cross-section grooves 75—75. Within the bearing openings 70—70 of the arms 69—69 there are rotatably engaged cylindrical bushings 76 and 77, the bushing 76 being of the same thickness as the arm 69 engaged thereby, and the bushing 77 projecting outwardly from the arm 69 with which it is engaged, and upon the inner faces of each of these bushings there are provided, in diametrically extending relation to the apertures therein, semi-circular cross-section ribs 78—78 which engage the grooves 75—75, of the inner joint member 72 and thereby rigidly lock this inner joint member to the bushings 76 and 77. A tie bolt 79 having a head at one end extends through the openings of the bushings 76 and 77 and through the bore of the tubular inner member 72 and being locked to the bushing 77 by a cross-pin 80.

Upon the projected end of the bushing 77 there is engaged the hub of a tension adjustment lever 81 which is secured thereto by means of a set screw 82, the end of this lever being provided with a threaded opening 83 in which is engaged an adjusting screw 84 having a hand wheel or nut 85 at its end, this adjusting screw bearing against a projected ear 86 integrally formed upon the frame member 65.

The outer joint member 71 is engaged in a cylindrical tubular bearing member 87, and is secured thereto against rotation by means of a set screw 88, this bearing member 87 being provided with an upwardly extending bracket arm 89 to which are secured the uprights 56 of the chair back, the bearing member 87 and arm 89 constituting a tilting back supporting member.

A forwardly projected lug 90 is integrally formed upon the bearing member 87 and is provided with an inclined under face 91 which engages the upper inclined face 92 of an angle adjusting cam member 93 slidably engaged upon the frame member 65. This cam member is provided with a threaded passage 94 which is engaged by a feed screw 95, having bearing in a pair of ears 96—96 integrally formed upon the upper surface of the frame member 65, and which is provided at its end with a hand wheel 97. By turning the feed screw 95 the cam member 93 is slidably moved upon the frame member 65 and through its inclined upper surface imparts rotary adjustment to the bearing member 87, thereby angularly adjusting the position of the chair back with relation to the chair seat. The torsional pressure produced in the rubber body 73 tends to rotate the member 87 in clock-wise direction, as seen in Fig. 5, and thereby presses the lug 90 against the cam member 93.

By adjusting the tension screw 84 the amount of tension in the joint member may be regulated, the movement of the lever 81 in clock-wise direction setting up increased tension in the rubber body, so that the resistance to tilting of the back is increased, as desired.

It will be seen that the engagement of the lug 90 with the cam member 93 limits the forwardly tilted position of the chair back. In order to provide a limit for the rearward tilting movement I provide a lug 98 upon the bearing member 87, which contacts a lug 99 formed upon the frame member 65 in the rearwardly tilted position of the back.

In Fig. 8 I have illustrated another modified form of the invention in which the joint member is mounted in relation to the centrally disposed

pedestal member 100 of the chair seat 12, this member 100 being rotatably mounted upon the base of the chair in any suitable manner, so that the chair seat may swivel in the usual manner. 5 On the upper portion of the member 100 there is integrally formed a block portion 101 disposed between the angle-iron spider arms 13-13 and secured thereto by means of screws 102, and also integrally formed upon this member 100 there are provided a pair of cylindrical tubular bearing portions 103-103 within which is engaged the joint member, similar to that of the embodiment shown in Figs. 1 to 4 and 9, and comprising the outer tubular member 18, the inner tubular member 19, and the cylindrical rubber body 20 interposed between them. The structure is substantially the same as that illustrated in Figs. 1 to 4 and 9, except that the tilting back supporting frame member 23a is considerably longer, so that it extends from the joint member to the rear of the seat where it is provided with the same vertical and angular adjustment means. The sides of the member 23a are connected near the forward ends by means of a rib 104 which bears upon the movement limiting flanges 29-29 formed upon the bearing portions 103, these flanges being provided as in the embodiment shown in Figs. 1 to 4 and 9, with angularly disposed movement limiting surfaces 30 and 31. The tension adjustment lever 32 projects vertically downward and the adjustment screw 36 bears upon a bearing boss 105 formed upon the pedestal member 100.

In Figs. 11 to 13 and 14 I have illustrated a further modified form of the invention, in which the joint element is provided at the upper end of the vertical chair back supports, these supports 106-106 being of right-angular form and having their lower ends secured to the angle-iron spider arms 13-13 of the chair seat 12 by means of rivets 107. A bracket member 108 is provided at its lower end with a transversely extending mounting portion 109 having flanges 110 at its ends, and which is secured to the upper ends of the supports 106-106 by means of bolts 111. The upper end portion of the bracket 108 projects forwardly in right angular relation and is provided with a pair of cylindrical tubular bearing portions 112-112 within which are engaged the ends of the joint element. The joint element 50 in this case comprises an outer tubular member 113, an inner cylindrical spindle member 114, and a cylindrical body of rubber 115 between them, and which, as in the other embodiments of the invention is in effect bonded at their surfaces. 55 The ends of the outer tubular member 113 are rotatably engaged in the bearing portions 112-112, and the spindle member 114 is provided at one end with a reduced extension 116 upon which the hub portion of a tension adjustment lever 117 is secured by means of a set-screw 118, a tension 60 adjusting screw 119 having a hand wheel 120 being engaged in an ear 121 integrally formed upon the frame member 108 and bearing upon the end of the lever 117.

The tilting chair back supporting bracket 122 is provided with a cylindrical bearing portion 123 engaged upon the outer member 113 of the joint element between the bearing portion 112-112, and secured thereto by means of a set-screw 124. 65 A rearwardly projected lug 125 is formed upon the bearing portion 123 and is engaged by an adjustment screw 126 having a hand wheel 127 at one end and which bears upon a bearing portion 128 70 formed upon the bracket member 108 and which

through adjustment adjusts the angularity of the chair back with respect to the seat 12.

Upon the forward face of the bracket member 122 there is formed a vertically disposed rib 129 which is engaged by a vertically disposed groove 5 130 provided in the chair back supporting member 131, this member 131 being provided with a vertical slot 132 engaged by a bolt 133 set in the bracket member 122 and having an end nut 134 upon its end which bears against the member 131 10 to secure the same in vertically adjusted position. By loosening this nut the member 131 may be vertically adjusted with respect to the bracket member 122 in order to obtain vertical adjustment of the chair back with relation to the chair 15 seat.

The ends of the member 131 are provided with forwardly bent ears 135-135 to which ears 136-136 formed upon the chair back 137 are pivotally connected by means of studs 138-138. A downwardly projecting ear 139 is provided centrally of the member 131, in which is engaged an adjustment stop screw 140 having a lock nut 141, and against which the back of the seat bears beneath the pivotal axis of the studs 138-138. 25 Adjustment of this screw 140 adjusts the angle of the chair back with respect to the member 131.

In operation, rearward rivet pressure against the chair back 137 swings the bracket member 122 downwardly in clockwise direction as seen in 30 Fig. 11. This action imposes a torsional strain in the rubber body 115 in substantially the same manner as described in connection with the other embodiments. Due to the relatively short lever arm between the axis of the joint member and 35 the point of engagement of the user's back with the chair back 137 a substantially smaller joint element may be employed with the same effect than is the case where there is a substantially longer lever arm, as in the embodiments shown 40 in Figs. 1 to 4 and 9, 5 to 7 and 10, and 8.

In Figs. 15 to 17 I have shown a further modification in which the joint element is mounted upon the chair back. A transversely extending member 142 is secured to the upper ends of the 45 supports 106 in substantially the same manner as employed in the embodiment shown in Figs. 11 to 13 and 14 by means of bolts 143, and is provided with a vertically extending standard 144 provided upon its rear face with a vertically extending rib 145 which is engaged by a vertical extending groove 146 provided in a bracket member 147, a bolt 148 extending through a slot 149 formed in the standard 144 being engaged through a bearing portion 150 formed in the bracket 147 and 50 having a hand nut 151 screwed thereon for securing the bracket 147 to the standard 144, the bracket adapted to be vertically adjusted with 55 relation to the standard by loosening the nut 151.

At the upper end of the bracket 147 there is 60 provided a flange portion 152 extending at an upward angle of approximately 45° and upon this flange portion there is formed a cylindrical tubular bearing portion 153. A tilting back supporting frame member 154 is pivotally connected at its sides to the bearing portion 153 by means of a tie-bolt 155 extending through the bearing portion 153, there preferably being a rubber or other type of oil-less and noiseless bearing bushing 156 interposed between the 65 bearing portion 153, and the bolt 155 carrying the tilting frame member, so that the latter is permitted to have tilting movement relative to the bearing portion 153 without metal to metal frictional contact. The tilting frame member 70 75

154 has its two side portions connected by a transversely extending rib 157 and at the forward ends of the two sides there are integrally formed a pair of spaced cylindrical tubular bearing portions 158—158, the joint element comprising the outer tubular member 159, the inner tubular member 160, and the cylindrical body of rubber 161 between them, being engaged in these bearing portions 158—158. The ends of the inner joint member 160, which project with respect to the rubber body, as in the first embodiment of the invention, are provided with semi-circular cross-section diametrically extending grooves 162—162 which lockingly engage diametrically extending ribs 163—163 formed upon the inner surfaces of rearwardly extending arms of a U-shape bracket 164 secured to the chair back 165, a tie bolt 166 having a head at one end and extending through the apertures in the arms 164 and through the bore of the tubular member 160 and being secured by means of a nut 167.

A tension adjustment lever 168 has its hub portion secured upon the outer joint member 159 by means of a set screw 169, and is provided with an adjusting screw 170, having a hand nut 171 engaged in a threaded passage 172 in its end and bearing upon the rib 157.

The flange 152 is provided at its forward edge 30 with an ear 173 in which is engaged an adjustment limit stop screw 174 bearing upon the under side of the rib 157. An upwardly projecting ear 175 is formed upon the bearing portion 153 and is also provided with a limit stop adjustment screw 176 against which the upper side of the rib 157 engages in the rearwardly pressed position of the chair back. By adjusting the screw 174 the normal front to rear position of the chair back with respect to the chair seat 12 may be adjusted to suit the particular user of the chair, and by adjusting the screw 176 the limit of rearward tilt may be regulated as desired.

At the lower portion of the chair back there are provided a pair of U-shaped brackets 177—177 to which the forward ends of a pair of flexible strap members 178 are connected by cross-pins 179—179, the rearward ends of these straps being connected by studs 180—180 to the bracket member 147. The axes of the joint element and the cross-pins 179, and the axes of the bearing 153 and the studs 180, are respectively in parallel vertical planes, and the tilting frame member 154 and the strap members 178 are in inclined parallel planes, so that the structure forms a parallelogram. The normal tendency of the chair back under the torsional pressure of the joint element is to swing in counter-clockwise direction, as seen in Fig. 15, the bracket 164 tending to straighten out with respect to the tilting frame member 154, but due to the connection of the lower end of the chair back to the bracket member 147 by means of the straps 178—178 the bracket 164 is pulled in clock-wise direction and the tilting frame member is normally pulled down against the stop 174 under the torsional pressure of the joint element. As rearward pressure is applied by the user against the chair back the tilting frame member 154 swings rearwardly in counter-clockwise direction, this action imposing tension in the joint element. By adjusting the screw 170 the initial tension set up in the joint element may be adjusted to suit the particular requirements of the user of the chair, this initial tension deter-

mining the resistance of the joint to rearward pressure upon the chair back.

I have illustrated and described preferred and satisfactory embodiments of the invention, but it will be obvious that changes may be made 5 therein, within the spirit and scope thereof, as defined in the appended claim.

Having thus described my invention, what I claim and desire to secure by Letters Patent is:—

1. A chair having a seat supporting frame element, a seat carried thereby, and a back element, and joint means connecting said back element to said frame element whereby said back element is adapted to have back and forth movement with respect to said seat comprising a pair of joint members one within the other and a rubber torsion sleeve member between said joint members interiorly bonded to the inner joint member and exteriorly bonded to the outer joint member, said sleeve holding one of said joint members in concentric spaced relation to the other, means fixedly connecting one of said joint members to said frame element, means fixedly connecting the other of said joint members to said back element, said torsion sleeve member being tensioned in a direction to force said back element forwardly in the direction of said seat, and stop means adapted to limit the forward movement of said back element under pressure of said torsion member, said back element adapted to be moved rearwardly relatively to said seat under the rearward pressure of the occupant of said seat and to further tension said rubber sleeve member. 35

2. A chair having a seat supporting frame element, a seat carried thereby and a back element, and joint means connecting said back element to said frame element whereby said back element is adapted to have back and forth movement with respect to said seat comprising a pair of joint members one within the other and a rubber torsion sleeve member between said joint members interiorly bonded to the inner joint member and exteriorly bonded to the outer joint member, said sleeve holding one of said joint members in concentric spaced relation to the other, means fixedly connecting one of said joint members to said frame element, means fixedly connecting the other of said joint member to said back element, 40 said torsion sleeve member being tensioned in a direction to force said back element forwardly in the direction of said seat, stop means adapted to limit the forward movement of said back element under pressure of said torsion member, said back element adapted to be moved rearwardly relatively to said seat under the rearward pressure of the occupant of said seat and to further tension said rubber sleeve member, and stop means adapted to limit the rearward movement of said back element whereby in the rearward limit position the back of the occupant is solidly supported by said stop means and the degree of tension applied to said torsion sleeve member is limited to a predetermined extent. 50

3. A chair having a seat supporting frame element, a seat carried thereby, and a back element, and joint means connecting said back element to said frame element whereby said back element is adapted to have back and forth movement with respect to said seat comprising a pair of joint members one within the other and a rubber torsion sleeve member between said joint members interiorly bonded to the inner joint member and exteriorly bonded to the outer joint member, said 70

sleeve holding one of said joint members in concentric spaced relation to the other, means fixedly connecting one of said joint members to said frame element, means fixedly connecting the other of said joint members to said back element, means arranged to retain one of said joint members in relatively rotated position with respect to the other joint member to initially tension said torsion sleeve member to force said back element 10 forwardly in the direction of said seat, stop means adapted to limit the forward movement of said back element under pressure of said torsion member, said back element adapted to be moved rearwardly relatively to said seat under the rearward pressure of the occupant of said seat and to further tension said rubber sleeve member.

4. A chair having a seat supporting frame element, a seat carried thereby, and a back element, and joint means connecting said back element to said frame element whereby said back element is adapted to have back and forth movement with respect to said seat comprising a pair of joint members one within the other and a rubber torsion sleeve member between said joint members 25 interiorly bonded to the inner joint member and exteriorly bonded to the outer joint member, said sleeve holding one of said joint members in concentric spaced relation to the other, means fixedly connecting one of said joint members to said frame element, means fixedly connecting the other of said joint members to said back element, adjustment means arranged to rotate and retain one of said joint members relatively to the other joint member to apply variable initial tension to 30 said torsion sleeve member in a direction to force said back element forwardly in the direction of said seat, stop means adapted to limit the forward movement of said back element under pressure of said torsion member, said back element adapted to be moved rearwardly relatively to said seat under the rearward pressure of the occupant of said seat and to further tension said rubber sleeve member.

5. A chair having a seat supporting frame element, a seat carried thereby, and a back element, and joint means connecting said back element to said frame element whereby said back element is adapted to have back and forth movement with respect to said seat comprising a pair of joint members one within the other and a rubber torsion sleeve member between said joint members 45

interiorly bonded to the inner joint member and exteriorly bonded to the outer joint member, said sleeve holding one of said joint members in concentric spaced relation to the other, means fixedly connecting one of said joint members to said frame element, means fixedly connecting the other of said joint members to said back element, adjustment means arranged to rotate and retain one of said joint members relatively to the other joint member to apply variable initial tension to 10 said torsion sleeve member in a direction to force said back element forwardly in the direction of said seat, said adjustment means being normally fixed with respect to said one joint member during movement of said back element, stop means 15 adapted to limit the forward movement of said back element under pressure of said torsion member, said back element adapted to be moved rearwardly relatively to said seat under the rearward pressure of the occupant of said seat and to further tension said rubber sleeve member.

6. A chair having a seat supporting frame element, a seat carried thereby, and a back element, and joint means tiltably connecting said back element to said frame element, whereby said back 25 element is adapted to have back and forth tilting movement with respect to said seat, comprising a pair of joint members one within the other and a rubber torsion sleeve member between said joint members 30 interiorly bonded to the inner joint member and exteriorly bonded to the outer joint member, said sleeve holding one of said joint members in concentric spaced relation to the other, means fixedly connecting one of said joint members to said frame element, means fixedly 35 connecting the other of said joint members to said back element, means arranged to retain one of said joint members in relatively rotated position with respect to the other joint member to initially tension said torsion sleeve member in a 40 direction to force said back element forwardly in the direction of said seat, stop means adapted to limit the forward movement of said back element under pressure of said torsion member, said back element adapted to be tilted rearwardly 45 relatively to said seat under the pressure of the occupant of said seat and to further tension said rubber sleeve member, the angle between said back element and said seat being increased as said back element is tilted rearwardly.
